HOT AIR REGISTER

Casimir J. Ochs, Andrew L. Ochs, and Raymond B. Ochs,
Seattle, Wash.

Application August 2, 1954, Serial No. 447,232

4 Claims. (Cl. 98—40)

This invention relates to what are known in the heating and ventilating art as "registers," and it has reference more particularly to improvements in registers that are designed primarily for use in conjunction with baseboard hot air heating systems as installed for residence heating purposes.

More specifically stated, the present invention pertains to the provision of an air discharging register wherein provision is made for directional control of the air in respect to its upward or its downward discharge from the register.

It is the principal object of the present invention to provide a register that is especially designed for use in a hot air baseboard heating system and which is provided with a valve element that is manually adjustable to direct the outflowing air either in an upward, or in a downward direction, or, if it is so desired, to effect the discharge of definite proportionate amounts of air in the two directions above mentioned.

Further objects of the invention reside in the details of construction and combination of parts embodied in such registers and in their mode of use, as will herein-after be fully described.

In accomplishing these and other objects of the invention, we have provided the improved details of construction, the preferred forms of which are illustrated in the accompanying drawings, wherein:

Fig. 1 is a perspective view showing an arrangement of registers for baseboard heating wherein the registers embody the improvements of the present invention therein.

Fig. 2 is a plan view of the registers as arranged in Fig. 1.

Fig. 3 is a cross-sectional view of a register, showing the valve element thereof adjusted to a position for effecting an upward discharge of air from the register.

Fig. 4 is a similar cross-sectional view of the register, showing the valve element thereof adjusted to a position for a downward discharge of air therefrom.

Fig. 5 is a perspective view of the valve member, detached from the housing, and as seen from the inside.

Fig. 6 is a view of a register of an alternative form of construction wherein the valve member is vertically slidable for its adjustment instead of being pivotally movable.

Fig. 7 is an enlarged cross-section, taken on the line 7—7 in Fig. 6.

Fig. 8 is a cross-section of a register showing a construction similar to that of Fig. 6 but having a different means of support for the adjustable valve member.

Fig. 9 is an enlarged section taken on line 9—9 in Fig. 8.

Fig. 10 is a cross-section of a register of still another form of construction, having a sliding damper plate for controlling the directional discharge of air therefrom.

Fig. 11 is a sectional detail in perspective, showing the valve securing lever.

Referring more in detail to the drawings:

The present register, as provided for use in baseboard heating systems, contemplates that it be made in several

2

standard lengths. For example, registers may be two feet, three feet or four feet in length, and adapted to be placed end to end to extend along a wall for any desired, or required distance. It is further anticipated that each register will have a suitable connection for its reception of heated air from an air supply duct. To illustrate this general arrangement of parts, I have, in Fig. 1, shown a succession of registers embodied by this invention, each designated in its entirety by numeral 10. These registers are arranged end to end, along a wall. Below the floor, upon which the registers are arranged, is a hot air supply duct 12 and leading from this duct to the individual registers, are connecting ducts 13. In this particular illustration, the ducts 13 connect with the registers through openings in their bottom walls, but it is to be understood that connections may, if desired, be made in like manner through their back walls, as has been indicated by the showing of duct 12x in Fig. 4.

Each register, preferably, is made of sheet metal and as will be understood best by reference to Figs. 3 and 4, comprises a vertical back wall 15, a horizontal bottom wall 16, and a horizontal top wall 17 which has a flange 18 depending vertically from its forward edge. The bottom wall 16 is provided along its forward edge with a vertically upturned flange 19 that leads into a continuing upwardly and inwardly inclined wall portion 20 which is formed along its upper edge with a vertically downturned flange 21. At its opposite ends, the register housing is closed by vertical end walls 22—22; all these wall forming parts being rigidly fixed together and non-flexible.

It will be observed by reference to Figs. 3 and 4, that the front forming parts 19 and 20 along the bottom of the register are slightly outset from the vertical plane of the flange 18 and the front is open except for the disposition therein of an adjustable valve member whereby the direction of discharged air is controlled.

The valve member is herein designated in its entirety by reference numeral 25. It comprises a single piece of sheet metal, that extends to the full length of the housing 40 between the end walls 22—22 thereof, and at its ends it is formed with inturned flanges 26—26 which lie closely parallel to and at the inside of the corresponding end walls 22—22, and are pivoted thereto by suitable means such as pivot studs 27—27 that permit the valve member 45 to be pivotally adjusted about a horizontal axis that is approximately midway between top and bottom edges of the valve member.

The plate 25 is angularly bent along a horizontal line, that is about two-thirds the distance from the bottom to top edge to provide an inwardly and upwardly directed portion formed at its top edge with a downturned flange 30 that is adapted, in one position of adjustment of the valve, to close flatly against the downturned flange 18 of the top wall 17. Along its lower edge, the member 25 is formed with an upwardly and inwardly bent flange 32 that is adapted, in another position of adjustment of the valve member, to close flatly against the inclined wall portion 20 of the front wall 19. Thus, it will be understood, that the valve member 25 is pivotally mounted for adjustment between the two positions in which it has been shown, respectively, in Figs. 3 and 4. Furthermore, it will be understood that in the position of Fig. 4, it provides an open space, as at 33, along the bottom of the housing between the flanges 20 and 32, through which air is caused to be discharged downwardly and outwardly from the housing and when in the position of Fig. 3, an opening 34 will be provided between flanges 18 and 30 for the discharge of air from the register in an upward direction.

At other positions of its adjustment of the valve element 25, between those in which it is shown in Figs. 3 and 4, the discharge of air through both passages 33 and

34 in proportionate amounts, as determined by the particular position of the valve member, is permitted.

It is anticipated that the valve 25 be held in any position to which it is adjusted by frictional contact between its end flanges 26-26 and the end walls 22-22 of the register housing to which the valve is pivotally attached.

As an alternative construction of the register and different mode of adjusting its valve element, I provide the details of construction and arrangement of parts shown in Fig. 6. In this view, the register housing is formed along the top edge of the front opening with a downwardly and inwardly inclined flange 18x in lieu of the vertical flange 18. Otherwise, the housing construction here shown is substantially like that previously described. The valve element, designated in this view by numeral 25c, is mounted for vertical sliding adjustment by means of screws 40 passed through vertical slots 41 in the opposite end flanges 26-26 of the valve and through holes 43 in the opposite end walls 22 of the housing. The screws are threaded into nuts 44 that seat against the insides of flanges 26. When the screws are loosened, the valve element can be lowered along the slots to close against the flange 20, or it can be lifted to close against flange 18x. Upon tightening the loosened screws, the adjustment will be retained.

Another alternative arrangement of parts is shown in Fig. 8 wherein the various parts of the register are like those of Fig. 6 both in construction and mode of use, but the valve element 25 is here adjustably supported at its opposite ends from brackets 48 that are fixed to the back wall of the housing and extend forwardly therefrom. The plate 25 here used is formed near its ends with vertical slots 49 each of which received a screw 50 therethrough. These screws are applied through the slots and are affixed to the brackets in the same manner as the valve mounting screws are fixed to the flanges 26 in Fig. 7, and adjustments of the valve are made and secured in the same manner.

In Fig. 10, we have illustrated still another form of construction wherein the register housing is closed at the front by an arcuately curved wall 51. This wall is formed along its top edge with a row of upwardly opening outlets 52 and along its bottom with a row of forwardly opening outlets 52'. A damper plate 53 is adjustably supported at the underside of the arcuate wall for upward and downward sliding adjustment to cover either set of openings 52 or 52' and to open the other set, or to partially cover both sets of openings and thus control the proportionate outflow through both sets, or to entirely cover both sets.

The damper plate 53 is supported closely against the inside of wall 51 and supported by bolts 54 passed through slots 57 in the outer wall and fixed to the damper plate as in the showing in Figs. 6 or 8. These bolts are provided with handles 58 for loosening or tightening to provide for adjustment and securing of adjustments.

While the device, as shown in Figs. 3 and 4, is now preferred because of its simplicity of construction and easy mode of operation, each of the others, likewise, provides for a positive control of the direction of outflowing air, either to cause it to be discharged horizontally along the floor, thus to clear such obstructions as draw drapes or curtains which may otherwise be a hindrance to good circulation, or to discharge upwardly, which may be desirable when no obstructing objects, such as drapes or curtains, are encountered.

The advantage of quick and easy adjustment of the single valve element for each register, which takes care of both sets of outlets, will be readily apparent to those familiar with this art.

Such registers may likewise be used to advantage for cold air circulation or for ventilating air and it is not the intent that they be restricted to use in heating plants.

Having thus described our invention, which we claim as new therein and desire to secure by Letters Patent:

1. A hot air register comprising a horizontally directed tubular duct equipped to receive air thereinto under pressure; said duct having a front wall opening extending the length thereof, with its top and bottom edges located near the top and bottom limits of the duct, and a valve member applied within said front wall opening, means supporting said valve member for turning in opposite directions on a horizontal axis between a first position at which it is closed against the top edge of the wall opening and provides an air discharge slot between its lower edge and the lower edge of said wall opening, and a second position at which it is closed against the bottom edge of said wall opening and provides an air discharge slot between its top edge and the top edge of said wall opening; the upper and lower edge defining parts of said valve and of the said front wall opening of the duct comprising flat inturned flanges so related as to coact, when opened apart, for the downward directing of air discharged at the lower edge of the valve and for an upward directing of air at the top edge of the valve, yieldable means for holding said valve member at a set position of adjustment, at either limit or at any position between its limits.

2. A register of the character described comprising an air duct adapted for disposition along the baseboard portion of a room and equipped to receive air thereinto under pressure for forced discharge therefrom; said duct having a front wall formed lengthwise thereof with an opening, a valve member disposed in said opening, means supporting said valve member in said opening for adjustment between two limits as established by the upper and lower edge defining portions of said opening, and providing when moved to the upper limit, an air discharge slot between its lower edge and the lower edge of said opening, and when moved to its lower limit of adjustment, providing an air discharge slot between its top edge and the top edge of said valve opening; said front wall of said duct being formed along the top and lower edges of said opening with air directing flanges, and said valve member being formed along its upper and lower edges with air directing flanges; said flanges as formed along corresponding edges of opening and valve member coacting to establish the direction of outflow of air as discharged from the duct through as established between them.

3. A register as recited in claim 2 wherein the flanges as applied to the edges of the valve member and along the edges of said opening, coact to effect a forward and upward discharge of air from the higher slot and provide for a forward and downward discharge of air from the lower slot.

4. A register as recited in claim 2 wherein said valve member is pivotally supported from the duct to swing from one limit of its adjustment to the other about a horizontal axis, and said flanges as formed along the upper and lower edges of the valve and duct opening are so directed that cooperatively arranged flanges will close flatly together.
